UNITED STATES PATENT OFFICE.

THEODOR QVILLER, OF LILLESTRÖMMEN, NEAR CHRISTIANIA, NORWAY.

PULSATING SCREEN FOR PULP AND THE LIKE.

1,124,802.

Specification of Letters Patent.

Patented Jan. 12, 1915.

Application filed November 11, 1913. Serial No. 800,333.

To all whom it may concern:

Be it known that I, THEODOR QVILLER, a subject of the King of Norway, residing at Lilleströmmen near Christiania, Norway, have invented certain new and useful improvements in Pulsating Screens for Pulp and the like; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to pulsating screens for pulp and the like and has for its object to provide a new screening apparatus of the kind referred to, the main feature of the said new apparatus consisting in its having no reciprocating parts to cause undesirous vibrations and shocks during the operation of the screen.

My invention consists in the features of construction and combination of parts hereinafter described and illustrated on the accompanying drawings and more particularly as pointed out in the claims.

On the drawings: Figure 1 shows a cross section and Fig. 2 a longitudinal section through a constructional embodiment of my invention. Fig. 3 is a section on line A—A on Fig. 2. Fig. 4 shows a cross section of a modified form of the apparatus and Figs. 5 and 6 show longitudinal and cross-section respectively of another modification.

B is the screen which is formed as a cylinder and is completely submerged in the pulp which is introduced at A. The inlet pipe A is made easily removable to make the several parts of the apparatus accessible. Inside the screening-cylinder is placed a second rotating cylinder D having two longitudinal suction channels S, and two longitudinal pressure channels T with openings on the cylinder surface. The long annular space between the rotating cylinder D and the screening cylinder B is divided by means of longitudinal radial partitions I into separate chambers C, five such chambers being provided. At each end of the cylinder D the suction and pressure channels are connected with a centrifugal pump N which tends to maintain a constant suction and pressure respectively in the channels by means of the pump blades O and guide

vanes P. As shown in Fig. 2, the pressure channels T are closed at their ends and communicate through their sides with the space in the pump casing between the periphery of the latter and the outer ends of the blades so that the pump acts to force the water and stock in said channels toward the screen. The suction channels are open at their ends and communicate with the pump casing between the inner ends of the blades and the axis of rotation of the latter so that the pump tends to draw the water from the suction channels. The stock sucked into the suction channels is partly let out at Q (Fig. 3) and partly let into the pressure channels. The receptacle enclosing the screening cylinder is provided with an easily removable cover R and at its bottom has openings G which may be opened or shut by means of a lattice slide operated from the lever M. At the cylinder ends removable covers W, are provided so as to allow for cleaning the suction and pressure channels when the pump-wheels are disengaged from the rotating drum D so that they can be rotated independently of same and uncover the openings of the channels. Through the openings G the stock can be let out into the chamber F under and to one side of the main receptacle. Near the openings G on both sides shower pipes U and V are provided. The chamber F has a grate- or perforated bottom H which slopes toward an opening K provided with a gate or a valve. On a level with the top of the screen-cylinder the chamber F communicates by means of one or more pumps or similar fluid-transporting means with the main-tank, said pumps or means keeping up a continuous circulation of the mass between the chamber F and the main-tank. The outlet openings from the pumps J have non-return valves or clappers L. Instead of pumps ejectors J may be used, (Fig. 4) part of the new pulp being used for ejecting purposes.

The operation of my apparatus is the following: The pulp to be screened is introduced at A in a quantity large enough to wholly cover the screen cylinder. The cylinder D is rotated so as to create suction and pressure in the channels S and T by means of the pump N, the wheels of which are rotated together with the cylinder D. Each time one of the suction channels S is brought into connection with one of the chambers C

under the screen surface the pulp stock is sucked through the screen and the suction-channels into the pump N, from where parts of the stock is let out through the pipe Q, while the rest is pressed into the pressure channels T by means of the vanes P. As the rotation of the cylinder D is continued a pressure channel is brought to coöperate with the chamber C above referred to and the pressure will cause the coarser fibers of the stock adhering to the screen plate to be expelled from the same. The chambers C being one more in number than the suction and pressure channels, it is impossible for any of the chambers C to be exposed at the same time to suction and pressure. The part of the mass introduced at A and through the pumps J and which is not sucked through the screen plate sinks down to the bottom of the receptacle and is let out through the openings G to the chamber F. In the bottom of the main receptacle the shower pipe U will prevent the mass from packing. Through the openings G the stock together with waste and coarser particles flows into the chamber F, which is provided near its bottom with the grate H through which a continual stream of water is flowing in an upward direction taking with it the fine fibers of the stock and leaving the coarser particles and the waste on the grate. The finer fibers are returned by means of the pumps J to the main receptacle, where they are again exposed to the screening action.

When a sufficient quantity of coarse pulp has accumulated on the grate H in the chamber F narrowing the area available for the flow of stock to a certain degree the velocity of flow will increase so that the coarser particles will also follow the current. To prevent this the openings G are closed at certain intervals by means of the lattice slide connected to the lever M and the waste is let out through the opening K. Owing to the non-return clappers L the fibrous mass from the main receptacle is prevented from flowing into the chamber F during the emptying of same. The cleansing therefore can be effected without stopping the machine and as soon as the chamber F is emptied and the grate washed by means of the shower pipe V, the opening K is closed, and the connection between the main receptacle and the chamber F is reestablished. The removable side wall R serves to facilitate inspection and repair of the interior parts of the screen.

Referring now to the modification shown on Figs. 5 and 6 the two suction channels S are here placed as shown near the outer surface of the rotating cylinder D, only one pressure channel T₁ being provided in the middle of the cylinder having two openings one on each side of the cylinder D.

Only one pump is used at one end of the

cylinder D to create suction in the two channels S and pressure in the pressure channel T. Guide vanes P arranged on the stationary end part of the apparatus to guide the mass into the channel T₁. The 70 screened pulp passes through the channel T₁ into the end chamber N₂ and out through the pipe Q. To keep pressure in the channel T₁ a pressure tank X is connected to the pipe Q as shown on Fig. 6, this tank having an adjustable partition Y by means of which the pressure in the channel T₁ may be controlled. The screened pulp flows over the partition Y and is let out at Z.

It is evident that the apparatus hereinbefore described can be modified in different ways within the scope of my invention. Thus for instance the screening cylinder might be made rotatable instead of the inner cylinder and the ribs I may be fixed on the 85 inner cylinder instead of the outer, etc. Also it is not necessary to form the two parts B and D as cylinders, the same effect may be attained by means of rotating disks or cones.

I claim:

1. In pulsating screens for pulp and the like a stationary screening cylinder, longitudinal radial ribs inside said cylinder dividing the cylinder into several sections, and a rotating member adapted to expose the several 95 sections of the screen alternately to the action of pressure and suction channels.

2. In pulsating screen for pulp and the like a stationary screening cylinder, a rotating cylinder therein, being provided with 100 suction and pressure channels having longitudinal openings on the surface of the cylinder, longitudinal radial ribs in the annular space between the inner rotating cylinder and the stationary screening cylinder, 105 said longitudinal ribs dividing the said annular space into several sections which are exposed alternately to the action of the pressure and suction channels of the rotating cylinder.

3. In pulsating screens for pulp and the like, a stationary screening cylinder, a rotating cylinder therein, provided with suction and pressure channels having longitudinal openings on the surface of the cylinder, and a pump in connection with the rotating cylinder for creating pressure and suction in the respective channels of the cylinder longitudinal radial ribs in the annular space between the inner rotating cylinder 120 and the stationary screening cylinder, said longitudinal ribs dividing the screening cylinder into several sections, which are exposed alternately to the action of the pressure and suction channels of the rotating 125 cylinder, part of the pulp sucked into the suction channels being pressed by means of the pump-vanes into the pressure channels.

4. In pulsating screens for pulp and the like, a screening cylinder, a main receptacle 130

inclosing said cylinder and adapted to be filled with pulp stock so as to completely cover the screening cylinder, an auxiliary chamber so connected with the said main receptacle that a continual circulation of the mass takes place from the said main receptacle to the said chamber and back again to the main receptacle.

5. In pulsating screens for pulp and the like a pulsating mechanism, a main receptacle inclosing the latter, an auxiliary chamber in connection with said receptacle, said main receptacle having openings leading to the said auxiliary chamber, a lattice slide for 10 closing the said openings, a sloping grate in the bottom of the auxiliary chamber and below the said openings, means in the auxiliary chamber for effecting a circulation of the stock between the auxiliary chamber and 15 the main receptacle, said auxiliary chamber having an opening at the lower end of the 20 said sloping grate for expelling waste and the coarser particles accumulated on the grate.

25 6. In pulsating screens for pulp and the like, a main receptacle inclosing the pulsating mechanism, an auxiliary chamber in connection with said receptacle, said main receptacle having openings in its bottom 30 leading to the said auxiliary chamber a sloping grate in the bottom of the latter and below the said openings, and means for driving a slow current of water in an upward direction through the said grate, the 35 said current taking with it the finer fibrous particles and leaving the waste and the coarser particles on the grate.

7. In pulsating screens for pulp and the like, a main receptacle inclosing the pulsating mechanism, an auxiliary chamber in connection with said receptacle, said main receptacle having openings in its bottom leading to the said auxiliary chamber, a sloping grate in the bottom of the latter and 45 below the said openings, pumps in the upper part of the auxiliary chamber for effecting a circulation of the stock from the chamber to the main receptacle and non-return clappers for preventing the stock 50 from returning to the auxiliary chamber when said chamber is emptied.

8. In pulsating screens for pulp and the

like, a main receptacle inclosing the pulsating mechanism, an auxiliary chamber in connection with said receptacle, openings in 55 the bottom of the said main receptacle and leading to the said auxiliary chamber, a lattice slide for closing the said openings, a sloping grate in the bottom of the auxiliary chamber and below the said openings, and 60 shower pipes near the said openings and the said grate partly to prevent the stock from packing in front of the said openings and partly for washing the grate.

9. In pulsating screens for pulp and the like, a stationary screening cylinder, a rotating cylinder therein, provided with suction and pressure channels having longitudinal openings on the surface of the cylinder, longitudinal radial ribs in the annular space 70 between the inner rotating cylinder and the stationary cylinder, a pressure chamber in connection with the said pressure channels receiving the separated pulp pressed through the pressure channels, an outlet pipe from 75 said pressure chamber and means for adjusting the pressure in said pressure chamber.

10. In pulsating screens for pulp and the like, a stationary screening cylinder, a rotating cylinder therein, provided with suction and pressure channels having longitudinal openings on the surface of the cylinder, longitudinal radial ribs in the annular space between the inner rotating cylinder 80 and the stationary cylinder, a pressure chamber in connection with the said pressure channels for receiving the separated pulp pressed through the pressure channels, 85 an outlet pipe from said pressure chamber, 90 a pressure tank connected with said outlet pipe, an adjustable partition in the pressure tank for controlling the head of fluid in the latter and the pressure in the pressure chamber the separated stock flowing over the said 95 partition in the pressure tank.

In testimony that I claim the foregoing as my invention, I have signed my name in presence of two subscribing witnesses.

THEODOR QVILLER.
